UNITED STATES PATENT OFFICE.

PETER P. BILHORN, OF CHICAGO, ILLINOIS.

PORTABLE ORGAN.

Application filed November 24, 1924. Serial No. 751,783.

To all whom it may concern:

Be it known that I, PETER P. BILHORN, a citizen of the United States, and a resident of the city of Chicago, in the county of Cook and State of Illinois, have invented certain new and useful Improvements in a Portable Organ; and I hereby declare that the following is a full, clear, and exact description of the same, reference being had to the accompanying drawings, and to the numerals of reference marked thereon, which form a part of this specification.

This invention relates to portable organs and more particularly to the type shown and described in my prior U. S. Patent No. 533,780, granted February 5, 1895.

It is the object of this invention to provide an organ of the above type to simplify the form of the parts to render the same more quickly and conveniently manipulated for folding and unfolding.

It is also the object of this invention to provide an organ of the above type which is more rugged and rigid than those used heretofore.

With the above and other objects in view as will be apparent, this invention consists in the construction, combination and arrangement of parts, all as hereinafter more fully described, claimed and illustrated in the accompanying drawings.

On the drawings:

Figure 1 is a perspective view of the organ unfolded in position for operation.

Figure 2 is a perspective view of the same folded for transportation.

Figure 3 is a front elevation of the same partially unfolded.

Figure 4 is a cross section of the organ casing partly unfolded with the organ mechanism left out.

Figure 5 is a cross section of the device as shown in Figure 2.

Figures 6 and 7 are detail views.

As shown on the drawings:

Numeral 1 represents a body portion of a folding organ of the type shown and described in my above mentioned Patent No. 533,780, having edges 2 adapted to coact with edges 3 of a second body portion 4 when the organ is in folded position. Inner end pieces 5 rigidly secured within the ends of body portion 1 are adapted to telescope into body portion 4.

The organ mechanism proper is secured between the end pieces 5 within the body

portion 1 in the same manner as shown in my above mentioned patent. A bellows 6 is secured beneath said organ mechanism and is adapted to be operated by pedals 7 in the usual manner. A handle 6^a flexibly supported on a suitable strap 6^b attached to the portion 1 is adapted to be utilized for pulling the organ from folded to unfolded or operative position. A hook member 8 is adapted to hold the bellows 6 in compressed position by means of engagement with a screw 8^a on said bellows. Brackets 9 are hinged beneath the lower edges of end pieces 5 and said brackets are provided with spring means 10 (see Figure 3) for normally impelling the same into folded position.

Along the inner edges of the bottom of body portion 4 as viewed in Figure 1 are reinforcing strips 11. When the brackets 9 are unfolded to support the organ in operative position, said brackets 9 rest on the top of said strips 11 and are retained thereon against the action of spring 10 by disks 12 which are secured near the upper edge of said strips 11 (see Figure 6). The brackets 9 are also held in operative position as shown in Figure 1 by means of hook members 13 on the body portion 4 adapted to engage with screws 14 projecting on the lower ends of said brackets 9. Collar members 15 are provided on screws 14 for providing a more secure engagement therewith by the hooks 13.

A cover 17 adapted to close the upper side of the organ as shown in Figure 1 is provided with screws 18 which are adapted to be engaged by the hook members 13 for locking the organ in closed position as shown in Figure 2. A hook 19 on the cover 17 is adapted to engage with a hook 20 on the base of body portion 4 as shown in Figure 2 for assisting in locking the organ in closed position.

In order to unfold the organ it is obviously only necessary to disengage the hooks 13 and 19 from the position shown in Figure 2, raise the body portion 1 about the hinges 21, and unfold the brackets 9 against the action of springs 10 to supporting position. The brackets 9 may be first placed in position to be caught by the disks 12 and then hooked in position by the hooks 13. The hook 8 is then disengaged and the cover 17 thrown back.

It will be obvious that since the brackets 9 are normally spring pressed in folded position that when it is desired to fold the organ

again it will not be necessary to reach into the space beneath the bellows 6 and hold said brackets 9 in folded position against the bottom of said bellows during the organ 5 folding operation.

It will also be apparent that the structure has been simplified and made more rigid.

I am aware that many changes may be made, and numerous details of construction 10 may be varied through a wide range without departing from the principles of this invention, and I therefore do not purpose limiting the patent granted hereon, otherwise than necessitated by the prior art.

15 I claim as my invention:

1. In a portable organ, a casing comprising a pair of sections adapted to be moved relative to each other into open or closed position, one of said sections being adapted 20 to support therein an organ mechanism, a pair of brackets adapted to support said section in position relative to the other of said sections for operation of said organ and means for normally impelling said brackets 25 into inoperative folded position within said section.

2. In a portable organ, a casing comprising a pair of sections adapted to be moved relative to each other into open or closed 30 position, one of said sections being adapted to support therein an organ mechanism, a pair of brackets adapted to support said section in position relative to the other of said sections for operation of said organ, 35 means for normally impelling said brackets

into inoperative folded position within said section and means for retaining said brackets in supporting position against the action of said first mentioned means.

3. In a portable organ, a casing comprising a pair of sections adapted to be moved relative to each other into open or closed position, one of said sections being adapted 40 to support therein an organ mechanism, a pair of brackets adapted to support said section in position relative to the other of said sections for operation of said organ, means for normally impelling said brackets 45 into inoperative folded position within said section and means for retaining said 50 brackets in supporting position against the action of said first mentioned means, said second means being also adapted to hold said sections in closed position.

4. In a portable organ, a casing comprising a pair of sections adapted to be moved relative to each other into open or closed position, one of said sections being adapted to support therein an organ mechanism, a pair of brackets adapted to support said 55 section in position relative to the other of said sections for operation of said organ and means for rigidly holding said brackets in supporting position, said means being 60 also adapted to hold said sections in closed 65 position.

In testimony whereof I have hereunto subscribed my name.

PETER P. BILHORN.
